FEED MECHANISM FOR KNITTING MACHINES

Harry Swinglehurst, Orange, N. J., assignor to
Scott & Williams, Incorporated, New York,
N. Y., a corporation of Massachusetts

Application March 9, 1932. Serial No. 597,721

20 Claims. (Cl. 66—133)

This invention pertains to knitting machines,—being concerned with devices for feeding yarns to the knitting instrumentalities, and especially relating to feeding means of the kind 5 designed to permit yarn interchange or the substitution of one yarn for another at the feed point. Modern knitting machines, particularly hosiery machines, are commonly provided with a plurality of independent yarn guides, often as 10 many as six, adapted respectively to deliver yarn of different size, quality, material, color, etc., for use either singly or in appropriate combination or relation in knitting different parts of a stocking, the several yarn guides usually being selectively 15 controlled by appropriate pattern mechanism, for example, such as disclosed in the patent to Scott, No. 1,152,850, dated September 7, 1915.

In the attainment of pattern effects in the 20 knitted structure (the term "pattern effects" being here employed as inclusive inter alia of such contrasting areas as high splices above the heel,—reinforced or spliced heels, soles, etc.) it is common to have recourse to the expedient of 25 plating a body or facing yarn upon a backing or splicing yarn in definite relation, and/or to substitute one yarn for another, the initial taking of such backing or substituted yarn necessarily occurring accurately in a certain pre- 30 determined wale or upon a definite needle at each successive course in order sharply to define the border of the desired patterned area. To secure such accuracy of taking of the entering yarn by a selected needle of the series, 35 it is essential that the delivery eye of the yarn finger move to a delivery position very close to the needle circle in order to splice the yarn accurately in between adjacent needles. Commonly the latch or guard ring or equivalent 40 structure of the machine is cut away at the feed point to produce a throat opening within which the active yarn finger or fingers is located, and usually this throat opening has a floor or 45 throat plate serving as a support upon which the active yarn guide rests with its delivery eye in a predetermined horizontal plane and close to the needle row. In passing from the active yarn guide eye to the needle hooks, the yarn reeves over the edge of this floor or throat plate so 50 that such edge actually defines the delivery point for any given yarn.

Since practical considerations make it necessary to give the individual yarn guide fingers some substantial lateral width, it is evident that 55 when more than one such guide finger is used,

the actual point of yarn delivery varies according to the guide which at any given time is in operative position. For plating any given yarn upon another, such as a body or facing yarn or yarns on a splicing or backing yarn, this relation is 60 taken advantage of to produce the different lead angles necessary to cause one yarn to enter the needle hook in accurately spaced relation to the other yarn so as to be plated thereon with certainty, but when it is desired to use more than 65 one such splicing or backing yarn alternatively, the above-noted relation causes difficulty in that the delivery points for the several splicing or backing yarns are not ordinarily the same, and thus the accuracy of plating the body or facing 70 yarn with one such splicing yarn, for example, may be destroyed. I am aware that it has heretofore been proposed to provide the latch ring or its equivalent with a yarn feed opening having a flaring mouth and so to dispose the several 75 yarn guide members behind the ring as to cause the yarn from any guide which is active to enter the feed opening through such flaring mouth so as to deliver to the needles from a single predetermined point, but this arrangement makes no 80 provision for desirable difference in feed point between a body or facing yarn and the splicing or backing yarn, nor would it be practicable in most modern hosiery machines where limitations 85 of space are often controlling.

The principal object of the present invention is to provide for the accurate delivery to the needles, from substantially the same delivery point, of any of a plurality of yarns, for instance, two splicing or backing yarns which are 90 used alternatively in the production, for example, of contrasting patterning areas in the knitted fabric. In particular the present invention provides for the permissive use of yarn feeding devices of a generally well known type 95 in knitting hosiery, wherein a body or facing yarn has associated therewith, at different parts of a stocking, either one, respectively, of a plurality of other yarns knitted as backing or splicing yarns in plated relation to the facing or body yarn. For example, the body or facing yarn may be plated over a backing or splicing yarn to produce a tapered high splice, and over a second backing or splicing yarn in knitting 100 a reinforced sole.

Thus the invention may be found useful in making spliced structures of a general type such, for example, as that illustrated in the patent to Page, No. 1,726,410, August 27, 1929 or that illustrated in the patent to Paquette, No. 1,723,881, 110

August 6, 1929; or the split-foot structure disclosed in the patent to Scott, No. 1,159,873, November 9, 1915.

While reference has been made to the plating 5 of a single facing or body yarn over a backing or splicing yarn, it is to be understood that the invention is equally applicable when a plurality of facing or body yarns are employed, as is often done, and wherein one of such body yarns is 10 knitted in plating relation to another, both being simultaneously plated over the splicing or backing yarn. Further, it is to be noted that when two yarns are fed in plating relation, each 15 yarn is plated relatively to the other, so that either yarn may be considered as a "plating yarn", and this term is to be understood with the meaning herein.

Other objects and advantages of the invention will be described more fully hereinafter and 20 will be apparent to those skilled in the art by reference to the appended drawings, in which

Fig. 1 is a fragmentary plan view, partly in section, of a knitting machine of known construction showing in particular novel features of 25 yarn feed mechanism in accordance with the present invention;

Fig. 1^a is a fragmentary horizontal section substantially on the line 1^a—1^a of Fig. 2;

Fig. 2 is a fragmentary side elevation of the 30 parts shown in Fig. 1;

Fig. 3 is a plan view similar to Fig. 1, but showing the splicing or backing yarn guides in relatively reversed position, one of the guides being broken away;

Fig. 4 is a fragmentary side elevation of the parts positioned as shown in Fig. 3;

Figure 4^a is a section on the line 4^a—4^a of Figure 4;

Fig. 5 is a fragmentary view similar to Fig. 3, 40 but showing a modified construction;

Fig. 6 is a fragmentary side elevation of the parts shown in Fig. 5;

Fig. 6^a is a section on the line 6^a—6^a of Fig. 6.

Fig. 7 is a fragmentary detail view of one of 45 the splicing guides of Figs. 5 and 6, viewed from from the inside of the needle circle;

Fig. 8 is a fragmentary view similar to Figs. 3 and 5 but illustrating a still further modification;

Fig. 9 is a fragmentary side elevation of the parts shown in Fig. 8;

Fig. 10 is a fragmentary detail view of one of the splicing guides of Fig. 8 viewed from the inside of the needle circle;

Fig. 11 is a diagrammatic view showing in 55 plan the course of a single body or facing yarn and one of the splicing or backing yarns as they pass from their respective guides to the needles;

Fig. 12 is a view similar to Fig. 11 but showing 60 the first splicing or backing guide out of action and broken away, and the second splicing or backing guide in action;

Fig. 13 is a side elevation of a needle hook showing the relation of the yarn as delivered 65 thereto by the guides of Fig. 11; and

Fig. 14 is a view similar to Fig. 13, showing the relation in the needle hook of yarns fed as in Fig. 12.

Referring to the drawings, the present invention is here illustrated for convenience in description and by way of example as embodied in a machine of the general type more fully disclosed in the patent to Scott No. 1,159,873, dated November 9, 1915, which prescribes sectional splicing mechanism of broad utility and

capable, if desired, of producing a plurality of distinct spliced areas circumferentially of the knitted tube, for example, in split foot knitting, and in the following description parts disclosed in said patent are designated by the same numerals as employed therein. It is to be understood that whether the present invention be applied to a machine such as shown in the above patent or not, the machine in which it is embodied will comprise the usual knitting instrumentalities and actuating means, and that proper pattern controlled devices will be provided for determining the proper sequence of operation of the knitting instrumentalities and for moving the several yarn guides into and out of action. Acceptable means for moving the yarn guides into and out of action is disclosed in the patent to Scott just referred to.

In the present drawings the numeral 552

(Figs. 1 and 2) designates the pivotal support for the latch ring bracket carrying the latch ring

550, such latch ring having the usual throat opening provided with a floor or "throat plate"

559, which constitutes a support for the active yarn guide or guides. The latch ring bracket is furnished with the upstanding part 555 which

carries the shaft or pivot member 554 upon which the several yarn fingers F¹, F², F³, etc. are, pivoted so that they may swing vertically

in substantially parallel planes. The several yarn fingers are provided with springs F⁸ conveniently anchored to the pivot member 552 and

tending to pull the several yarn fingers downwardly into active position where their delivery

eye portions rest upon the throat plate 559. The web holder bed 295 (Fig. 2) is provided with

peripheral, segmental cams 296^a and 296^b (Figs. 2 and 4), disposed in different horizontal planes and such cams are adapted to actuate motion

transmitting levers 601 and 602 respectively, pivotally supported to move in horizontal planes, all as more fully described in the aforementioned

patent to Scott, No. 1,159,873. The several yarn fingers are moved out of active position by means of the thrust bars 460^a, 460^b,

etc., such thrust bars at their lower ends resting upon a suitable cam drum (not herein shown but

described in the aforesaid patent) having cams properly arranged to move the thrust bars up

and allow them to drop in suitable sequence. The upper portions of these thrust bars pass

through a fixed guide comb 462 by means of which they are guided in their movements. The

thrust bar 460^a corresponds to the yarn finger

F¹ and the thrust bar 460^b corresponds to the

yarn finger F², and the thrust bars just mentioned are furnished respectively with projecting

lugs a and b adapted to cooperate with the

levers 601 and 602 respectively, under certain

conditions of operation. The several yarn guide

fingers are provided with guide eyes E¹, E², E³ etc., near their free extremities, such guide eyes

exemplifying any suitable means for locating

the delivery point of the yarn leading from the

yarn finger and in fact constituting the yarn

guides proper. In the present instance and by

way of example, the guide eye E¹ is intended

to carry a splicing yarn y¹ (Fig. 11),—the guide

eye E² is intended to carry a second splicing

145 yarn y² (Fig. 12),—and the guide eye E³ carried

by the third finger F³, is designed to carry a

body or facing yarn y³.

In accordance with the present invention, the

yarn finger F², which together with the other

145

150

5 fingers is pivoted on the shaft or pivot member 554, is provided with a bearing opening 1 (Fig. 1^a) which is preferably countersunk inwardly from opposite faces, and the adjacent surfaces 10 of this yarn guide finger F² are beveled or reduced in thickness so as to permit the finger 15 to swing laterally, as well as to rock in the vertical plane. To the rear of its pivotal axis the finger F² is furnished with a tail 2, to which is secured one end of a spring 3 whose other end 20 is anchored to a fixed bracket 4 conveniently secured to the upper end of the part 555. This spring constantly tends to swing the guide eye 25 end of the finger F² to the left, as viewed in Figs. 1 and 3, respectively.

25 Preferably the forward part of the finger F² is provided with upper and lower cam surfaces 6 and 5 respectively, (Figs. 2, 4 and 4^a), and if desired the finger F¹ may be provided with complementary cam surfaces, although such surfaces 30 on one of the cooperating fingers are usually sufficient.

35 In Figs. 1 and 2 the yarn finger F¹ is down in its operative position with its eye portion resting upon the throat plate 559, this position of the 40 yarn finger being permitted by the descent of its thrust bar 460^a. In thus descending, and as shown in Fig. 2, the lug a of this thrust bar has been brought into the plane of the lever 601, which at this time is shown as engaging a low or inactive portion of the cam 296^a on the web holder bed 295. At the same time the thrust bar 460^b has been raised, thus throwing the finger F² up to its inoperative position. The 45 yarn finger F³, which carries the body or facing yarn is down in its active position, while the yarn fingers to the right of the yarn finger F³ as viewed in Fig. 1, and shown in broken lines are raised to the inoperative position. With the 50 parts thus positioned, the splicing yarn y¹, (Fig. 11) will pass from the yarn guide eye E¹ around the corner 7 of the throat opening and will enter the hook of needle n (as shown in Fig. 13) at the outer part of the hook, while the body or facing yarn y³, passing from the guide eye E³ 55 will engage the edge of the throat plate at a point somewhat spaced from the corner 7 and will enter the needle hook near the back of the latter, as shown in Fig. 13. With this arrangement, the yarn y³ will be accurately plated on the yarn y¹, the latter being at the inside of the fabric. If the splicing is to occupy only a portion of a course, the cam 296^a may be provided 60 at the proper point or points with a high portion operative to swing the lever 601 and thereby, through the lug a, to swing the upper end of the thrust bar 460^a, thus moving the yarn finger F¹ temporarily into inactive position so that the splicing yarn y¹ will cease to be taken 65 by the needles. This motion of the yarn guide finger F¹ into and out of action during a portion of a knitted course may be caused to take place with great accuracy by the arrangements just described, all as set forth more fully in the 70 Scott Patent No. 1,159,873, above referred to.

75 If at any time during the knitting operation it be desired to substitute the splicing yarn y² from the guide eye E², the thrust bar 460^a may be elevated and the thrust bar 460^b may be moved downwardly, thus throwing the finger F¹ up and allowing the finger F² to move down. In Fig. 3 the finger F² which has been raised to idle position is broken off to show the guide eye E² in its active position. As above noted, the spring 3 tends constantly to swing the free

forward end of the finger F² to the left, as viewed in Fig. 1 and thus into the path of movement of the forward end of the finger F¹, but if the downward movement of the finger F² takes place concomitantly with the upward movement of the finger F¹, the cam surface 5 of the finger F², by engagement with the upper part of the finger F¹, will crowd the finger F² to the right so as to avoid interference between the fingers as they pass. As soon as the finger F² is free to do so, it will swing (by the influence of the spring 3) until its guide eye E² is disposed in the vertical plane of movement of the guide eye E¹, and as the finger F² reaches its feeding position where it rests upon the throat plate 559, its 80 guide eye will occupy substantially the same identical position that the guide eye E¹ occupied when the latter was in feeding position. Thus, as shown in Fig. 12, the splicing yarn y² will now pass around the corner 7 of the throat opening and will enter the needle hooks, as shown in Fig. 14 in the same relation to the body or facing yarn y³ as did the splicing yarn y¹ from the guide eye E¹. Thus the new splicing yarn y² will cooperate in the same way with 85 the body yarn y³ to produce a fabric wherein the body yarn is accurately plated over the splicing yarn. As above described in reference to the finger F¹, the finger F² may be thrown into and out of action for sectional splicing by 90 the operation of the cam 296^b on the web holder bed 295, acting through the lever 602 on the lug b. Whenever the splicing yarns are to be exchanged and the finger F² rises, the cam surface 95 6 of such finger will be acted on by the finger F¹ so as to crowd the finger F² laterally into its normal plane to prevent interference of the fingers as they pass. Furthermore, it is to be noted that if the finger F² be left down in its 100 normal feeding position when the finger F¹ is lowered to feeding position, the latter will crowd the finger F² out of its way as it descends so that both guide eyes E¹ and E² will be in normal 105 feeding position at once, resting on the throat plate 559. It is also possible to make sectional 110 spliced areas employing the respective splicing yarns, each such spliced area extending through a portion of the same course the fingers F¹ and F² being under control of the cams 296^a and 296^b respectively on the web holder bed. 115

120 Obviously, if it be desired, as is common, to use a plurality of body yarns plated one on the other, for example, a second body yarn in addition to the yarn y³, another of the yarn guides, for instance the fifth guide (not shown) from 125 the left hand side of the throat opening (Fig. 11) may be placed in delivery position to feed its yarn simultaneously with the yarn y³ and the selected splicing or backing yarn.

130 Referring to Figs. 5 to 7 inclusive a second embodiment of the invention is illustrated wherein corresponding parts are designated by the same reference numerals as above employed, but in this arrangement the finger F² always remains in a plane substantially parallel to the 135 finger F¹. However, the guide eye portion 8 of the finger F² is made as a separate independent part from the body portion of the finger and is pivoted thereto by means of a pivot pin or equivalent device 9 (Fig. 6), which, when the 140 finger is in its operative position, is preferably substantially vertical. A spring 10 secured at its opposite ends to the body of the finger F² and to the part 8 respectively, urges the part 8 to the 145 left, as viewed in Figs. 5 and 7, thus tending to 150

place the guide eye E^2 in the plane of movement of the finger F^1 . To prevent interference between the guide eye portions of fingers F^1 and F^2 , the part 8 is provided with cam surfaces 13 and 14 and preferably the finger F^1 is furnished with complementary cam surfaces 11 and 12, the cam surfaces acting in the same way as those previously described to crowd the part 8 of the finger F^2 laterally out of the way of the finger F^1 as the fingers are moved into and out of operative position. With this arrangement, when the finger F^2 is in delivery position, its guide eye E^2 occupies substantially the same identical position on the throat plate as the guide eye E^1 of the finger F^1 when the latter is in its operative position, so that accurate plating of the body yarn over either splicing yarn is assured in the same way as with the preferred construction of Figs. 1 to 4.

In Figs. 8 to 10 a still further modification is illustrated wherein the guide eye portion 15 of the finger F^2 is made as a separate part but is connected to the body portion of the finger F^2 by means of a spring member 16, such spring member being biased to swing the part 15 laterally into the normal plane of movement of the finger F^1 . The part 15 may be provided with a cam surface 17 and the finger F^1 may be furnished with cam surfaces similar to those shown in Figs. 6 and 6^a above described, such cam surfaces acting to prevent interference between portions of the fingers F^1 and F^2 as such fingers are moved into and out of action.

While I have herein disclosed certain desirable embodiments of means for securing the desired result, that is to say, for insuring accurately similar feed of any of a plurality of yarns, I wish it to be understood that the invention is not to be limited to these specific constructions, nor by the specific purpose or function of the yarns so fed, nor necessarily to the employment of but one laterally moving guide,—but is to be regarded as broadly inclusive of any equivalent means whereby the same or similar result is attained, and that changes in size, proportion and shape of parts may be made without departing from the spirit of the invention. It is also clear that the invention is not necessarily to be applied to a machine of the particular type herein disclosed or specifically referred to, but is applicable in its broader aspect to any knitting machine wherein a plurality of independently movable yarn guides are employed.

I claim:

1. Yarn feeding mechanism for knitting machines comprising a guide for a body yarn, a pair of guides for other yarns, and means to move either of said latter guides at will relatively to the body yarn guide into a common feeding position, whereby to ensure like association of either of said other yarns with the body yarn.

2. Yarn feeding mechanism for knitting machines comprising a guide for a facing yarn, a pair of independent guides for backing yarns, means operative to support said latter guides side by side in position to deliver their yarns simultaneously but at different lead angles, and means operative to move either of said backing yarn guides at will into a common plane substantially normal to the row of needles and parallel to individual needles and to a given point in such plane at a predetermined distance from the needles, whereby to ensure like association of either backing yarn with the facing yarn.

3. Yarn feeding mechanism for knitting ma-

chines comprising independently movable yarn guides operative at will simultaneously to feed each of a plurality of yarns to the needles from different delivery points and with different lead angles respectively, means operative to remove one of said guides from its delivery position so as to throw its yarn out of action, and means operative to cause another of said guides to shift from its first delivery position to that of the yarn guide which has been so removed.

4. Yarn feeding mechanism for knitting machines comprising a pair of guide members independently movable in planes substantially parallel to the needles, each having a yarn delivery eye, a member constituting a support for each of said guide members when in operative yarn feeding position, said supporting member having an edge over which the yarn passes from the active guide to the needles, and means operative to move either of said guide members alternatively so as to position its guide eye at substantially the same spot relative to said support, whereby the yarn from either eye passes over the same point on the edge of the support on its way to the needles.

5. Yarn feeding mechanism for knitting machines of the kind having yarn guides arranged in a series extending along the needle row, said machine comprising a member having a feed throat opening provided with a floor whose inner edge is disposed closely adjacent to the needle row and over which yarn reeves in passing to the needles, and means operative alternatively to place either of a group of the yarn guides in active delivery position upon the floor of said throat opening, while moving other guides of the group out of action, the delivery end of any guide of said group when in active position being at substantially the same distance from the inner edge of the floor and at the same distance from the lateral end of the throat opening, whereby yarn from either guide will reeve over the same point on said inner edge of the floor in passing to the needles.

6. Yarn feeding mechanism for knitting machines comprising a guide for a body yarn, a pair of guides for plating yarns, all of said guides being mounted to permit swinging movement to and from operative position in substantially parallel planes, a member having a feed throat opening provided with a floor over an edge of which the yarn reeves on its way to the needles, and means to cause the delivery ends of each of said plating guides to occupy a common position in the throat opening when delivering yarn to the needles, whereby each plating yarn will reeve over the same point on the edge of said floor, thereby ensuring similar association of each plating yarn with the body yarn in the knitted fabric.

7. Yarn feeding mechanism for knitting machines comprising a plurality of yarn guide fingers, means providing a substantially horizontal pivotal axis for each of said fingers, one at least of said fingers being pivoted to swing laterally as it is rocked upwardly or downwardly about the axis of its pivot from inoperative to operative position, and constantly acting means tending to swing said yarn finger so as to carry its delivery end substantially into the position previously occupied by an adjacent finger when the latter was in its delivery position.

8. Yarn feeding mechanism for knitting machines comprising a plurality of independently movable yarn guide eyes each adapted to occupy

- 6 a predetermined normal delivery position, independently operative means for moving said guide eyes toward and from such delivery positions respectively, and constantly acting resilient 80
- 5 means tending to cause one guide eye, as it is moved toward such normal delivery position, to preempt the normal delivery position of an adjacent guide eye if the latter is then in its inoperative position. 85
- 10 9. Yarn feeding mechanism for knitting machines comprising a plurality of movable yarn guide fingers each having a yarn delivery end, the delivery end portion of one finger being movable relatively to the finger proper, and means 90
- 15 tending to cause said movable delivery end to swing into the yarn delivery position of the delivery end of an adjacent guide when the latter is in its inoperative position. 95
10. Yarn feeding mechanism for knitting machines comprising a plurality of yarn guide fingers each having a yarn delivery end, the delivery end portion of one finger being hinged to swing laterally relatively to the plane of movement of the finger proper, and means for swinging said 100
- 25 hinged end laterally as the finger is moved from inoperative toward its operative position. 105
11. Yarn feeding mechanism for knitting machines comprising a pair of yarn guide fingers mounted for movement in substantially parallel 110
- 30 planes from inoperative to operative position, means tending to move the delivery end portion of one of said fingers into the normal delivery position of the second finger, and cam means carried by one of said fingers operative as the second 115
- 35 finger is moved to its delivery position to remove the delivery end of the first finger from said position. 120
12. Yarn feeding mechanism for knitting machines comprising a pair of yarn guide fingers mounted to permit them to swing in substantially parallel vertical planes, resilient means tending to move the delivery end portion of one finger laterally into the normal delivery position of the second finger as the first finger is 125
- 40 swung toward its operative position while the second finger is in inoperative position, and means operative to restore the delivery end portion of the first finger to a plane parallel to the body portion of the second finger as the 130
- 45 second finger is moved to its delivery position. 135
13. Yarn feeding mechanism for knitting machines comprising a pair of yarn guide fingers each having a yarn delivery end, means for moving said fingers to and from yarn delivery position, the delivery end portion of one finger at least being movable laterally relatively to the finger proper, and spring means tending to move said delivery end portion laterally as the finger proper is moved toward its operative position. 140
- 50
14. Yarn feeding mechanism for knitting machines comprising a plurality of movable yarn guide fingers each having a yarn delivery end, and means for moving the fingers to and from delivery position, the delivery end portion of one finger at least being connected to the body portion of the finger by a resilient yielding member which is biased to move said delivery end portion laterally of the finger proper as the latter moves toward its operative position. 145
- 55
15. Yarn feeding mechanism for knitting machines comprising a plurality of movable yarn guide fingers each having a yarn delivery end, means for moving the fingers toward and from delivery position, the delivery end portion of one finger at least being hinged to swing laterally 150
- 60 relatively to the finger proper, and spring means tending to swing said end portion laterally as the finger is moved toward its operative position. 155
16. Yarn feeding mechanism comprising a pair of yarn guide fingers mounted to permit them to swing in substantially vertical parallel planes, means tending to move the delivery end portion of one finger laterally into the normal delivery position of the end portion of the second finger as the first finger is moved into its operative position, and cam means carried by one at least of said fingers for crowding the delivery end portion of the first finger laterally back into a plane parallel with the second finger as the second finger moves toward delivery position. 160
17. Yarn feeding mechanism for knitting machines comprising a pair of yarn guide fingers mounted to permit them to move in substantially parallel planes, spring means tending to move the delivery end portion of one of said guide fingers laterally into the plane of the other finger, and cam means carried by one finger at least and operative as the fingers are moved relatively from operative to inoperative position and vice versa to restore said delivery end portion of the first finger to a plane substantially parallel with that of the second finger. 165
18. Yarn feeding mechanism for knitting machines comprising a pair of yarn guide fingers pivoted to permit them to swing in substantially parallel planes in moving from operative to inoperative position, yieldable means tending to move the delivery end portion of one finger laterally into the plane of the second finger, and cam means comprising opposed inclined surfaces on one of said fingers at least operative to move the delivery end portion of the first finger out of the plane of the second finger as the latter is moved toward delivery position. 170
19. Yarn feeding mechanism for knitting machines comprising a series of movable yarn guiding fingers which in idle position lie in planes substantially parallel to the needles, pivot means for one at least of said fingers, said latter finger having a bearing opening so shaped as to permit the finger to rock in a plane radial to the axis of the pivot and also to swing laterally with respect to said radial plane, means constantly tending to swing said finger laterally whereby to 175
- 20 cause its delivery end to lie substantially in the plane of an adjacent finger, means constraining the latter finger to move always in the same plane, means to move the several fingers independently toward and from operative position, and means operative as said pivoted finger is rocked to carry its delivery end to inoperative position to move the delivery end of the pivotal finger out of the plane of said adjacent finger. 180
20. Yarn feeding mechanism for knitting machines comprising means operative to cause three or more yarns to be delivered simultaneously, all from different points relative to the descending needle hooks at the knitting wave, and alternatively acting means operative to cause one of a pair of said yarns to be removed from delivery position and to cease feeding and concomitantly to shift the second of said pair of yarns to the delivery point previously occupied by the yarn which was removed, whereby to 185
- 25 insure similar positioning of either selected one of said pair of yarns with reference to a third yarn in the knitted fabric. 190
